UNITED STATES PATENT OFFICE.

GEORGE A. CLUFF, OF CLIFTON, NEW JERSEY.

WARPING-MACHINE.

1,377,751.

Specification of Letters Patent. Patented May 10, 1921.

Application filed March 24, 1920. Serial No. 368,235.

To all whom it may concern:

Be it known that I, GEORGE A. CLUFF, a citizen of the United States, residing at Clifton, in the county of Passaic and State 5 of New Jersey, have invented certain new and useful Improvements in Warping-Machines, of which the following is a specification.

This invention relates to warping machines, and particularly to warping machines wherein several warps are wound at once, as in ribbon or edge warping, the principal object being to effect the winding of the warps on separate receiving beams or 15 the like and to make provision for the stopping of the operation as to any particular warp when a predetermined length thereof has been wound. The invention consists in certain novel combinations of parts herein- 20 after pointed out in connection with the accompanying drawings and finally embodied in the clauses of the claims, said drawings showing in—

Figure 1 a side elevation of the improved 25 machine;

Fig. 2 a plan thereof;

Fig. 3 a section on line 3—3, Fig. 1;

Fig. 4 a side elevation of the principal 30 moving parts of the stopping mechanism;

Fig. 5 a plan of certain parts appearing 35 in Fig. 4;

Fig. 6 a view of certain parts as seen from 40 the side opposite to that appearing in Fig. 4; and

Fig. 7 illustrates a detail shown in Fig. 1 45 and viewed from the opposite side from which it is seen in that figure.

The creel carrying the spools from which 50 the warps are taken is shown by dotted lines at *a* in Fig. 1.

b designates a suitable frame for the improved warping machine, and *c* is a suitably driven drive-shaft on which at regular intervals are fixed the driving wheels *d*, said 55 shaft being suitably journaled in the frame.

e is a fixed shaft on which are brackets *f* and *g*, the former being fixed and the latter fulcrumed thereon; each bracket *g* may be 60 swung up to the limit afforded by a stop bar *h*. Each bracket *g* has a shaft *i* journaled therein in such manner that in any position of the bracket in moving around its fulcrum the shaft will stand substantially perpendicular to the bracket: in the illustrated 65 construction this is accomplished by providing a fast ratchet wheel *j* on the shaft

and securing to the bracket a fork *k* which straddles the shaft and holds the ratchet-wheel face to face with the bracket (Fig. 7). The ratchet wheel and hence the shaft is 60 kept from rotation except in one direction by a pawl *l*. On each shaft *i* is fixed a wheel *m*, adapted when the bracket is in the depressed position to rest in peripheral contact with one of the driving wheels *d*, at 65 which time the other or free end of said shaft *i* is supported by the bracket *f*, and on each shaft is adapted to be slipped a spool or beam *n* which preferably has a spline connection therewith, as indicated at 70 *o*. The removal from and placing of a spool or beam on a shaft is accomplished when the bracket is elevated in the way explained. The warps, it will be understood, 75 are wound up on the spools or beams *n*.

There is a bar *p* over which all the warps extend from the creel to their respective spools or beams. For each warp there are also a reed *q* and a tension bracket *r*, the reed being held in a clip *q'* which is clamped 80 to a fixed rod *p'* and the bracket being pivoted on said rod *p'* and having a roller *r'* under which the warp extends; for each warp there is also a drum *s* of relatively 85 large diameter over which the warp extends, the drum being free to rotate due to the friction between it and the advancing warp (which friction may be made effective for the purpose in hand by facing the periphery of the drum with felt or the like *t*) which 90 is made to have considerable contact with the periphery of said drum by the guide roller *r'* and a glass bar *u* arranged at the relatively opposite side of the drum and common to all of the warps. 95

In view of the foregoing it will be seen that the machine is constructed so that the warping operation as to each warp may be made to begin independently of all the others, and that as fast as each spool or beam becomes filled the operator can remove the filled spool or beam and substitute an empty one while the warping operation as to the other warps is going on. For each unit of the machine thus involved an individual means to stop the winding-up operation is provided, as will now be explained: 100

There is a strut *v* (Figs. 1, 2 and 3) extending across the frame and having downwardly and upwardly projecting brackets *w* 110 and *x* (it may also have brackets *y* to afford rigid support to the free ends of

brackets f). In each two brackets w and x are fulcrumed between their ends levers z and 2, respectively, the free ends of which respectively form a handle z' and a seat 2' and the other ends of which are connected by the link 3 (Figs. 1, 2, 3, 4 and 6) which depends somewhat below the levers, the lever system thus formed (being normally held in the full-line position shown in Fig. 4 by means to be explained but impelled by gravity toward the dotted-line position) serving as a shifter means for shifting the beam-including driven member out of contact with the driving member d . The means to hold the lever system in the full-line position is a curved hook-shaped detent 4 which may be fulcrumed on w concentric with the lever z and is adapted to hook over a pin 5 on the link 3; I prefer to provide a notch or step 6 on the link which will engage over a certain shaft 7 to be again referred to and assist the detent 4 to support the lever system when in the full-line position, especially since said lever system has attached thereto a weight 8 which insures a precipitous fall of the lever system when released. When the detent is pushed up to clear pin 5 the step 6 slips off shaft 7, due to the weight of the parts.

Means is provided to cause the releasing movement of the detent, the same being movable back and forth and normally impelled in one direction (as by gravity) and adapted to be fed or advanced in the other direction from the driven warp-engaged means (as drum s) to bring a part thereof into actuating engagement with said detent; and means is also provided (when the detent is released and the lever system shifts the beam-including driven member clear of the driving member d to stop the winding-up) to release the first-named means from the feeding instrumentality so that subject to the influence normally tending to move it contrary to its feeding movement it will be re-set for another operation. To these ends 10 is a ratchet-wheel journaled on the aforesaid shaft 7 around whose hub 11 (Fig. 5) is wound a cord 12 which extends over a pulley 13 and has a weight 14 attached thereto, so that due to gravity the ratchet wheel tends to rotate in one direction counter-clockwise until the cord has become completely unwound. The ratchet wheel is advanced in the other direction, step by step, from an eccentric 15 on the adjoining drum s through a strap 16 (Fig. 4) on the eccentric, a lever 17 connected with the link 16' of the strap and fulcrumed concentric with the ratchet wheel and a pawl 18 on the lever, 19 being a suitable holding pawl for the ratchet wheel which is fulcrumed on shaft e . On the ratchet wheel is also a sprocket wheel 20 around which and an idler 21 extends a chain 22 which travels through an

opening in a lug 23 on the detent and has a ball or enlargement 24 thereon adapted to impinge against the lug and trip the detent. Fulcrumed on lever 17 is a lifter 25 which is connected with link 3 by the flexible connection 26 and passes through an eye 25' on pawl 18 and has an eye 25" receiving pawl 19.

The operation is as follows: In the working position the parts of each unit stand as shown in Fig. 1 or in full lines in Fig. 4, wherefore, with shaft c rotating, the warp will be winding up on the beam u , and in consequence of the incidental rotation of the drum s the ratchet wheel 10 will by the instrumentalities described be turned against the influence of weight 14 step by step, winding up the cord 12 on the hub 11 of the ratchet wheel and advancing the chain 22. Ultimately the ball 24 on the chain will engage and trip the detent 4, whereupon the lever system will fall by gravity to the dotted line position and in doing so elevate the beam-including driven member clear of the driving member d , so that the warping operation stops as to the particular unit affected; the fall of the lever system also, through the connection 26, shifts the lifter 25 so that the pawls 18 and 19 are moved clear of the ratchet wheel, which then turns, 95 in the direction opposite to that in which it has been fed step by step, subject to the influence of weight 14 so as to set back the chain 22 to its original or starting position. Having removed the filled beam from shaft 100 i and substituted an empty one (upon elevating bracket g in the manner already fully explained) the operator has only to push down on handle z' to re-set the lever system or shifter means where it will be 105 supported by the detent and shaft 7, as explained, which operation of course leaves the beam-including driven member again in peripheral contact with the driving member d .

The operator may stop the driving of any beam at will by turning a cam-device or chock 26' (Fig. 1) so that its toe by resting on seat 2' of lever 2 raises wheel m clear of wheel d .

Having thus fully described my invention, what I claim as new and desire to secure by Letters Patent is:—

1. In a warping machine, the combination of a frame, driven warp-engaging means including a rotary member arranged in the frame, a rotating driving member, also arranged in the frame, one member being movable in one direction into, and in the other direction out of, peripheral contact with the other member, and means, controlled from the driven warp-engaged means, to shift the movable member in one direction.

2. In a warping machine, the combina- 130

tion of a frame, driven warp-engaging means including a rotary member arranged in the frame, a rotating driving member also arranged in the frame, one member being movable in one direction into, and in the other direction out of, peripheral contact with the other member, normally impelled shifter means adapted to shift in one direction the movable member, and means, controlled from the first-named means, to releasably hold the shifter means retracted.

3. In a warping machine, the combination of a frame, driven warp-engaging means including a rotary member arranged in the frame, a rotating driving member also arranged in the frame, one member being movable in one direction into, and in the other direction out of, peripheral contact with the other member, normally impelled shifter means adapted to shift in one direction the movable member, a movable detent holding the shifter means retracted, and means, driven by the first-named means, to move said detent and thus cause it to release the shifter means.

4. In a warping machine, the combination of a frame, driven warp-engaging means including a rotary member arranged in the frame, a rotating driving member also arranged in the frame, one member being movable in one direction into, and in the other direction out of, peripheral con-

tact with the other member, normally impelled shifter means adapted to shift in one direction the movable member, a movable 35 detent holding the shifter means retracted, detent actuating means movable back and forth and normally impelled in one direction and when moved in the other direction being adapted to engage the detent, and 40 means, driven from the first-named means and having a disconductive connection with the detent-actuating means, to move the latter in the direction to engage the detent, said connection being controlled by the 45 shifter means.

5. In a machine for winding warps and the like, the combination of a frame, a rotary driving member journaled in the frame and having its axis substantially horizontal, a bracket pivoted in the frame on an axis parallel with the axis of the driving member, and a rotary member including a shaft projecting from and journaled in said bracket parallel with the axis of the driving member and a wheel fixed on the shaft close to the bracket and adapted to rest on the driving member in peripheral contact therewith, said shaft having one end free and being adapted to receive a beam slipped 55 thereon over said end.

In testimony whereof I affix my signature.

GEORGE A. CLUFF.
